UNITED STATES PATENT OFFICE.

DAVISSON A. BENSON, OF FROSTBURG, MARYLAND, ASSIGNOR TO STANDARD ARCH COMPANY, OF FROSTBURG, MARYLAND, A CORPORATION OF MARYLAND.

FURNACE-ROOF STRUCTURE.

Application filed March 26, 1926. Serial No. 97,719.

My invention relates to furnace roof structures and is primarily designed to afford a simple, reliable and efficient construction which may be erected and repaired with a minimum expenditure of labor.

A more specific object of the invention is to provide a combination and arrangement of parts permitting metallic elements of simple form to be employed. Another object of the invention is to so form and relate the bricks to their metallic support and to each other that they may be readily brought into assembled relation and easily removed in the event replacements become necessary. A still further object of the invention is to form and relate the bricks in a manner enabling them to adjust themselves when assembled and to efficiently distribute the strains imposed upon them.

Other features of the invention residing in advantageous relations and forms of parts will hereinafter appear and be pointed out in the claims.

25 In the drawings illustrating preferred embodiments of the invention

Figure 1 is a vertical transverse section of the upper portion of a furnace involving a roof constructed in accordance with the invention.

30 Figure 2 is a detail sectional view, taken on the line 2—2, Figure 1.

Figure 3 is a detail view showing a portion of one of the carriers, the bricks associated therewith and the clip or cover for preventing removal of the bricks from the carrier.

Figure 4 is a detail sectional view on the line 4—4, Figure 3.

40 Figure 5 is a view corresponding to Figure 1 but illustrating a modified form of the invention.

Figure 6 is a transverse sectional view of a furnace illustrating a form of curved arch furnace roof embodying the invention.

45 In the drawings 1—1 are the side walls of the furnace and 2—2 are buckstays. The buckstays on opposite sides of the furnace are connected in the usual or any preferred manner by tie rods 3. Extending upwardly from the side walls of the furnace and rigidly secured in place, as by being riveted to adjacent buckstays 2, are oppositely disposed columns 4 whose upper ends sup-

port corresponding transversely extending beams 5. These beams are spaced from each other longitudinally of the furnace and may conveniently be in the form of I-beams. The upright columns 4 are preferably channels and the overhead beams 5 may be rigidly secured thereto through angle irons or brackets 6.

Suspended from each of the overhead beams 5 by means of a series of hanger devices 7 is a rigid brick supporting member 8 which is open on its underside. The hanger devices 7, as more particularly shown in Figure 2, may advantageously consist of angular or hook like members 9 which overlap the lower flanges of the overhead beam 5 and are connected by a bolt 10 to a threaded rod 11. This threaded rod cooperates with a turnbuckle 12 having threaded engagement with a rod 13 forming the lower element of the hanger. Where, as is preferred, the brick supporting members 8 are in the form of downwardly opening slotted cylindrical tubes, the material slotted from the tube may be punched and utilized as a bearing strip 14 for reinforcing the tube at its point of attachment to the hangers.

The rigid brick carriers 8 extend continuously from one side of the furnace to the other, preferably being integral and open ended and each formed from a hollow cylindrical metallic tube slotted on its lower side so as to provide downwardly converging walls or portions 15 for supporting bricks 16. Each of the bricks 16 is fashioned at its upper end with a head 17 adapted to be received within the tube 8, the head being preferably formed with lateral cylindrical faces corresponding to the curvature of the inner wall of the tube. By this means, as will be readily appreciated, the bricks 16 may adjust themselves angularly in accommodation to the strains imposed upon them. The upper ends of the heads 17 of the bricks 16 are suitably recessed to afford, as at 18, clearance for the lower ends of the hanger rods 13 and reinforcing members 14.

Each of the downwardly opening brick carriers 8 supports a single row of bricks 16. In order to permit the removal and replacement of independent bricks 16 without the necessity of disturbing all the bricks in

a row, each of the hollow brick carriers 8 is cut away or recessed intermediate its ends to form a lateral opening 19 which communicates with the slot in the bottom of the carrier. A plurality of the openings 19 is preferably employed, their spacing being governed generally by the width of the furnace and the thickness of the bricks employed. To support the bricks 16 positioned in overlapping relation to the openings 19, the brick carrier 8 preferably has mounted thereon a series of clips 20 for respectively covering the openings 19. A portion of each of these clips is provided with an inwardly extending projection or liner 21 (see Figure 4) which is adapted to fit into the correspondingly shaped opening 19 so as to make the inner wall of the brick supporting member 8 continuous. As the openings 19 and liners 21 of the clips are preferably tapered downwardly they cooperate to prevent the clips from rotating toward the body of brick thus insuring proper clearance. When a brick 16 is to be removed after the furnace has been erected the clip 20 which is nearest thereto is removed from the tubular member 8, as will be readily understood.

Intervening between each pair of adjacent rows of bricks and supported by the latter is an intermediate row of bricks 22. To facilitate grinding of the bricks so as to insure their proper size and the provision of suitable bearing surfaces, as well as to enable the bricks 22 to accommodate themselves to minor variations in the sizes and vertical positions of the bricks 16, the bricks 16 are preferably formed with outwardly and downwardly inclined lateral faces 23 upon which correspondingly inclined downwardly converging faces or shoulders 24 of the bricks 22 seat. In assembling the roof structure the intermediate rows of bricks are placed in position after the rows of bricks 16 have been brought into assembled relation with the brick carriers 8. Any brick 22 may be immediately removed and replaced if a new brick is required to be substituted therefor, but it will be observed that before a brick 16 can be disengaged from its carrier 8 it is necessary to remove one or more of the bricks 22 which are adjacent the opening 19 in the carrier through which the brick 16 is to be withdrawn. The intermediate bricks 22 therefore prevent removal of the bricks 16 even after the appropriate cover 21 for the opening 19 has been removed.

To limit undue shifting of the bricks 22 of the intermediate rows metallic straps 25 which are supported by the side walls of the furnace and extend across the ends of the row of bricks may be employed. A gas tight closure at the end of the arch may be provided by the use of the well known sand

seals 26 if desired. In assembling the bricks of the arch spacers of cardboard are preferably placed therebetween as is commonly done. When the furnace is fired these spacers are burned out, thus allowing for 70 expansion of the bricks.

In the construction shown in Figure 5 the tubular carriers 27 by which the bricks 16 are suspended are formed at their outer ends with down turned curved portions 28 which terminate at the top of the side walls 1 of the furnace. The space between the outermost bricks 16 and these curved portions 28 of the brick carriers is occupied by skew back bricks 29 which project into the tube 27 in a manner similar to the bricks 16. Except for these differences the construction shown in Figure 5 is identical with that illustrated in Figures 1 to 4 inclusive and heretofore described and accordingly similar parts have been identified with corresponding reference numerals.

Figure 6 illustrates a form of furnace roof construction showing the applicability of my invention to a curved arch roof. In this instance the tubular members 8 by which the bricks 16 are carried extend longitudinally of the furnace and are adjusted vertically by means of the turn buckle hangers 7 so as to assume proper elevations to 95 give the desired curvature to the arch.

The invention provides an efficient roof which may be readily erected and maintained and although preferred embodiments have been described with particularity it is 100 to be understood that changes in form and in the proportion of parts are contemplated within the spirit of the invention and the scope of the claims.

I claim:

1. A furnace arch construction involving an integral slotted tubular member adapted to support a plurality of bricks having heads received by said slotted tube, said member being provided with a cut out portion to permit the removal of bricks therefrom at a point intermediate its ends.

2. A furnace arch construction involving a brick supporting member adapted to embrace and thereby support a plurality of bricks, said member being provided with a cut out portion intermediate its ends to permit the removal of bricks therefrom, and means for supporting bricks positioned in said cut out portion involving a clip adapted to embrace said supporting member.

3. A furnace arch construction involving a plurality of rigid brick supporting members extending continuously from one wall of the furnace to the opposite wall thereof, spaced rows of bricks supported by said members, and rows of bricks intermediate said supported rows and carried by the supported rows, said rigid brick supporting members being fashioned to permit the re-

moval of bricks therefrom intermediate its ends only after the removal of bricks from said intermediate rows.

4. A furnace arch construction involving 5 a plurality of integral brick supporting members, spaced rows of bricks supported by said members, rows of bricks intermediate said supported rows and carried by said supported rows, each of said brick supporting members being provided with a cut out portion intermediate its ends to permit removal of bricks therefrom only after at least 10 one of the bricks in the intermediate row adjacent said cut out portion has been re- 15 moved.

5. A hollow brick supporting member for a furnace roof provided with a slot extending longitudinally thereof, said member having converging brick engaging shoulders enabling the bricks to adjust themselves in accordance with the strain imposed thereon, 20 one of said shoulders having a cut out portion to permit the removal of bricks from said member at a point intermediate its ends.

6. A furnace arch construction involving 25 a row of headed bricks, and a hollow integral member adapted to support a plurality of the bricks in the row, said member being provided with a slot extending longitudinally thereof, the portions of the member adjacent the slot being inclined to provide brick engaging faces, at least one of said faces being cut away to permit the removal 30 of bricks from the member at a point intermediate its ends.

7. A hollow integral brick supporting member adapted to support a plurality of bricks, a longitudinally extending slot therein, the walls of said member adjacent said 40 slot converging downwardly towards each other to form brick supporting shoulders, and a portion of at least one of the walls adjacent the slot being cut away to permit the removal of bricks from the supporting 45 member at a point intermediate the ends thereof.

8. A furnace arch construction involving 50 a plurality of rows of bricks, longitudinally slotted hollow supporting members for receiving the upper ends of the bricks, the walls of each of said members adjacent the slot converging downwardly towards each other to form brick supporting shoulders and a portion of at least one of the walls 55 adjacent the slot being formed with a recess permitting the removal of bricks from the supporting member at a point intermediate

its ends, and means respectively overlapping said recess for normally preventing withdrawal of said bricks.

9. A furnace arch construction involving 60 a rigid hollow cylindrical brick supporting member, means for supporting said member from above, and a plurality of bricks extending into said member and carried thereby, 65 said supporting member extending continuously from one wall of the furnace to the opposite wall thereof and provided with means permitting the removal of bricks therefrom at a point intermediate its ends.

10. A furnace arch construction involving 70 an integral hollow cylindrical brick supporting member having a longitudinally extending slot, a plurality of bricks extending into said member and supported thereby, 75 said member being provided with a portion to permit the removal of bricks therefrom at a point intermediate its ends.

11. A furnace arch construction involving 80 a plurality of integral tubular slotted brick supporting members, a plurality of bricks adapted to be engaged by each of the supporting members and supported thereby, each of said members having a cut out portion permitting the removal of bricks intermediate its ends, and means for supporting 85 the bricks in each of the cut out portions.

12. A furnace arch construction involving 90 a brick supporting member adapted to embrace and thereby support a plurality of 95 headed bricks, said member being provided with a cut out portion permitting the removal of bricks therefrom at a point intermediate its ends, and a member adapted to embrace the brick supporting member and engage the bricks positioned in said cut out portion.

13. A refractory brick, having at its upper 100 end a headed portion provided with downwardly converging bearing faces, oppositely disposed substantially parallel faces at its lower end, and intermediate faces converging upwardly toward the head and intersecting the parallel faces.

14. A refractory brick having at its upper 105 end a headed portion provided with substantially cylindrically curved bearing faces, oppositely disposed substantially parallel faces adjacent the opposite end thereof, and intermediate faces angularly disposed with 110 respect to the said parallel faces.

In testimony whereof I affix my signature.

DAVISSON A. BENSON.
